UNITED STATES PATENT OFFICE.

CARL AUGUST MÜLLER, OF WITZENHAUSEN, GERMANY.

LOCK.

1,173,677.

Specification of Letters Patent. Patented Feb. 29, 1916.

Application filed January 30, 1912. Serial No. 674,256.

To all whom it may concern:

Be it known that I, CARL AUGUST MÜLLER, a subject of the Emperor of Germany, residing at Witzenhausen, Germany, have 5 invented certain new and useful Improvements in Locks, of which the following is a specification.

The present invention relates to safety locks in which a rotatable locking cylinder 10 in a casing is locked by means of tumblers on which the key acts through separate intermediate elements.

According to the present invention the tumblers are so constructed that they do not 15 depend for their locking on the support afforded by the intermediate elements—that is to say, they continue to lock after this support is removed by the elements being destroyed. Moreover, the elements do not act 20 directly on the tumblers, but upon the ends of projections which extend laterally from the tumblers in a plane which crosses or intersects the plane in which the intermediate elements lie. Thus when the intermediate 25 elements and the tumbler projections are destroyed, the tumblers, which as explained above still continue to lock, are quite inaccessible to pick-locks and the like.

Figures 1, 2 and 4 of the accompanying 30 drawing show such a lock in cross-section, partly in longitudinal section and section on line A—A respectively while Fig. 3 shows the corresponding key. Figs. 5-16 show other constructions, partly in cross-section, 35 and partly in longitudinal section, Fig. 6 showing single tumblers, Fig. 9 being a section on line B—B of Fig. 8, Fig. 14 a front elevation of the lock shown in Fig. 13, and Fig. 15 showing the corresponding key.

In all the constructions illustrated, the 40 cylinder *a* rotatable in the casing *b*, is locked in the usual manner by means of tumblers *c* of which there can be provided any desired number. In addition to these tumblers there 45 could be provided further auxiliary tumblers *d* which become operative only when the locking cylinder *a* is partly turned, and even in that case only when the tumblers situated in the cylinder, are not accurately ad- 50 justed owing to the use of a wrong key or of a skeleton key. In the same way any de- 55 sired auxiliary recesses *e* can be provided in the casing, which prevent the locking cylinder from further rotation if the tumblers *c* are not correctly adjusted. The tumblers *d* and the auxiliary tumblers are provided

as usual with springs *f*. All these tumblers or locking parts can be arranged in the cylinders either in a radial or longitudinal adjustable manner. They are situated out of 60 reach of the key-hole *g*, and are completely closed off from the latter and inaccessible from the outside, and each of them locks the lock independently. They are operated by a key of any desired shape (for instance 65 Fig. 3 or Fig. 15) by means of a separate element *h* which partly projects into the key-hole and transmits the movement of the key to the locking parts. The element *h* can have the shape of a bar (Figs. 1, 2, 5, 7, 70 12, 13, 16) or be constituted by balls (Figs. 10 and 11) or have some other suitable shape. The element can also be provided with a projection *i* (Fig. 7) which projects into the key-hole, so that the element itself 75 is protected. Several such elements successively transmitting the movement of the key to the tumblers, could be used (Figs. 13-16). The elements *h* can then also act as locking parts, as in case of a wrong adjustment, they 80 lock together the parts *a* and *b*. In case of safes, the element *h* can be of such length that it projects into the door *k* (Fig. 16). In this figure, *l* is the engagement disk for the sets of bolts of the safe. In this case 85 the cylinder *a* is not turned by the key as in the other constructions, but by hand-operated means.

The tumblers could be provided with parts *m* (Fig. 6) which do not coöperate in 90 locking but are merely used for operating the elements *d*. The said parts could however also coöperate in locking (for instance Fig. 8). In all the constructions great security is insured owing to the fact that only 95 the element *h* can be destroyed, while the tumblers themselves are inaccessible from the key-hole, and continue to lock after the destruction of the element.

The lateral projections *d*² on the tumblers as shown have two functions, firstly to prevent the tumblers from falling out of their locking position when the intermediate elements are destroyed, and secondly to serve 100 as connecting means between the elements *h* 105 and the tumblers *c* and *d*.

What I claim as my invention and desire to secure by Letters Patent is:—

1. In a tumbler lock, a cylindrical casing having a plurality of recesses in the inner 110 face thereof, a cylinder rotatably mounted in said casing and having a key-hole, interme-

diate elements operable by a key and disposed in parallel recesses, tumblers disposed in recesses arranged in a plane laterally displaced from and parallel to the plane of the 5 said intermediate elements, lateral projections on said tumblers which extend at right angles to said tumblers into the path of the intermediate elements, and operate to retain the tumblers in locking position when the 10 intermediate elements are withdrawn or destroyed.

2. In a tumbler lock, a cylindrical casing having a plurality of recesses in the inner face thereof, a cylinder rotatably mounted in 15 said casing and having a key-hole, intermediate elements operable by a key and disposed in parallel recesses, tumblers disposed in recesses arranged in a plane laterally displaced from and parallel to the plane of the 20 said intermediate elements, lateral projections on said tumblers extending at right angles to said tumblers into the path of the intermediate elements, projections on said tumblers adapted to engage shoulders in the 25 recesses of the casing and to retain said tumblers in the recesses.

3. In a tumbler lock, a cylindrical casing having a plurality of recesses in the inner face thereof, a cylinder rotatably mounted 30 in said casing, and having a key-hole, intermediate elements operable by a key and disposed in parallel recesses, tumblers disposed in recesses arranged in a plane laterally displaced from and parallel to the plane of the 35 said intermediate elements, lateral projections on said tumblers extending at right angles to said tumblers into the path of the intermediate elements, extensions on said lateral projections, and secondary tumblers 40 adapted to be adjusted thereby, whereby the tumblers continue to lock when the intermediate elements are withdrawn or destroyed.

4. In a tumbler lock, a cylindrical casing having a plurality of recesses in the inner 45 face thereof, a cylinder rotatably mounted in said casing and having a key-hole, intermediate elements operable by a key, and disposed in parallel recesses, tumblers disposed in recesses arranged in a plane laterally displaced from and parallel to the plane of the 50 said intermediate elements, lateral projections on said tumblers extending at right angles to said tumblers into the path of the intermediate elements, extensions on said 55 lateral projections adapted to act as locking parts, and secondary tumblers adapted to be

adjusted thereby, whereby the tumblers continue to lock when the intermediate elements are withdrawn or destroyed.

5. In a tumbler lock, a cylindrical casing 60 having a plurality of recesses in the inner face thereof, a cylinder rotatably mounted in said casing and having a key-hole, intermediate elements operable by a key and disposed in parallel recesses, tumblers disposed 65 in recesses arranged in a plane laterally displaced from and parallel to the plane of the said intermediate elements, lateral projections on said tumblers extending at right angles to said tumblers into the path of the 70 intermediate elements, extra tumblers arranged in secondary recesses in the casing and adapted to lock in case of an attempt to force the lock, and means comprising lateral projections whereby the tumblers continue 75 to lock when the intermediate elements are withdrawn or destroyed.

6. In a tumbler lock, a cylindrical casing having a plurality of recesses in the inner face thereof, a cylinder rotatably mounted in 80 said casing and having a key-hole, rows of contacting balls operable by a key and disposed in parallel recesses, tumblers disposed in recesses arranged in a plane laterally displaced from and parallel to the plane of the 85 said rows of balls, and lateral projections on said tumblers into the path of the rows of balls, whereby the tumblers continue to lock when the rows of balls are withdrawn or destroyed. 90

7. In a tumbler lock for safes, a cylindrical casing having a plurality of recesses in the inner face thereof, a cylinder rotatably mounted in said casing and having a key-hole, intermediate elements operable by a 95 key passing through the door of the safe and disposed in parallel recesses, tumblers disposed in recesses arranged in a plane laterally displaced from and parallel to the plane of the said intermediate elements, lateral projections on said tumblers extending at right angles to said tumblers into the path of the intermediate elements, whereby the tumblers continue to lock when the intermediate elements are withdrawn or destroyed. 100 105

In testimony whereof I have signed my name to this specification in the presence of two subscribing witnesses.
